E. K. BOTTLE,
APPARATUS FOR REMOVING STAPLES,
APPLICATION FILED NOV. 4, 1911.

1,160,568.

Patented Nov. 16, 1915.

UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO.

APPARATUS FOR REMOVING STAPLES.

1,160,568.

Specification of Letters Patent.

Patented Nov. 16, 1915.

Application filed November 4, 1911. Serial No. 658,486.

To all whom it may concern:

Be it known that I, EDWARD KIRBY BOTTLE, a citizen of the United States, residing at Elmira, in the county of Chemung and State of New York, have invented certain new and useful Improvements in Apparatus for Removing Staples, of which the following is a full, clear, and exact description, such as will enable others skilled in the art 10 to which it appertains to make and use the same.

This invention relates to apparatus for removing staples, and with regard to the more specific features thereof, to apparatus 15 for removing the binding staples of books.

It is one of the objects of this invention to provide a simple and practical method and apparatus for quickly and efficiently removing the staples from the bound edge of 20 a book.

Another object is to provide a self-contained apparatus of the above nature that will be cheap to manufacture and rapid and convenient in use.

25 Other objects will be in part obvious and in part pointed out hereinafter.

In the accompanying drawings, wherein is described one of the various possible forms of my invention,—Figures 1 and 2 are fragmentary perspective views showing the manner in which the apparatus is used; Fig. 3 is a plan view of the blank of the staple-removing tool; Fig. 4 is a similar view of the finished article; Fig. 5 is a longitudinal sectional view of the article shown in Fig. 4; Fig. 6 is a plan view of the complete apparatus; and Fig. 7 is a detail sectional view of the tool-holding device.

Similar reference characters refer to similar parts throughout the several views of the drawing.

Conducive to a clearer understanding of this invention, it may be remarked that in the manufacture of sales books and similar articles a single order often comprises several thousand books. It sometimes happens that in filling such an order a defect in the manufacture of the pads occurs, in which case it is cheaper to remove the binding staples than to throw away the pads.

Referring to the drawings in detail, and particularly Fig. 6, 1 denotes a flat table or lap board provided with a transverse groove or longitudinal recess 2. Parallel with this 55 groove is a cleat 3 adjustable in a direction

transverse to its length by means of bolts or thumb screws 4 passing through the cleat and slots 5 in the board 1. Positioned at right angles to the cleat 3 is a second cleat 6 similarly adjustable in a direction transverse to its length by means of bolts 7 passing through slots 8. The cleats 3 and 6 are adapted to engage the end and side of a sales book, respectively, so that the binding staples 9 lie directly over the groove 2. At 60 one side of the board 1 is secured, by means of screws or other fastening means 10, a spring clip 11 provided with a headed stud 12. This stud 12 is adapted to engage and pass through an opening 13 having an adjacent narrowed slot 14 in a handle 15 of the staple-removing tool for taking under the head 12.

This tool, which is shown more in detail in Figs. 3, 4 and 5, is made from a sheet 75 metal blank shown in Fig. 3, and comprises a wedge-shaped or tapering staple-engaging end 16 which curves inwardly from the sides, as shown in Fig. 4, and also from the top and bottom as shown in Fig. 5. Substantially opposite about the width of the inside of the average staple, and extending from each side, are laterally projecting arms 17 having inwardly cut notches 18 so that when 85 the arms are folded over, as shown in Fig. 4, they provide an overhanging hood, the under side of which is adapted to engage the top of the staple, as shown in Fig. 2.

The method of operation or manner of 90 using this apparatus is substantially as follows: The board 1 is taken in the lap of the operator and the cleats 3 and 6 are set to engage the end and side of a book so that the staples may be positioned over the groove 95

2. The staple-removing tool is then removed from the spring clip 12 and is inserted beneath the clamped over ends of the prongs of the staple on the reverse side of the book, as shown in Fig. 1, and pushed 100 rearwardly at right angles to the plane of the staple, which causes the ends of the prongs of the staple, due to the curved tapering edges of the tool, to swing upwardly, as shown in the dotted lines. All of the 105 binding staples of one book are treated in this manner and then the book reversed so that these projecting ends extend into the groove 2. The same tool is then pressed down so as to take in under the top of the 110

staple and moved rearward until the top of the staple catches in under the hood 17, as clearly shown in Fig. 2. A further rearward and upward movement will withdraw the 5 staples. The hood, by engaging the top of the staple, positively prevents distortion and one side pulling out before the other, obviating the necessity for the use of pliers or other means for completing the operation.

10 The tool is then replaced on its holding clip while positioning the next book.

It is thus seen that this invention provides a simple and practical means for quickly and efficiently removing the staples 15 from books, and accomplishes, among others, all the objects and advantages above set forth.

As many changes could be made in carrying out the above method, and in the above 20 construction, and many apparently widely different embodiment of this invention could be made without departing from the scope thereof, it is intended that all matter contained in the above description or shown in the accompanying drawings shall be interpreted 25 as illustrative and not in a limiting sense.

Having described my invention, what I

Copies of this patent may be obtained for five cents each, by addressing the "Commissioner of Patents,
Washington, D. C."

claim as new and desire to secure by Letters Patent is:

30 1. A staple-removing tool comprising a handle, a forwardly extending wedge-shaped portion connected to said handle for engaging the under part of a staple, and transverse members above said wedge-shaped portion integrally connected thereto and terminating short of the forward end thereof, such transverse members extending forward to form a hood for the staple.

35 2. A staple-removing tool comprising a handle, a forwardly extending wedge-shaped portion integrally connected to the handle for engaging the under part of a staple, and transverse members above the wedge-shaped portion also integrally connected thereto and terminating short of the forward end thereof, but extending forward to form a hood for said staple; the tool formed 40 from a single integral piece of sheet metal.

45 In testimony whereof I affix my signature, in the presence of two witnesses.

EDWARD KIRBY BOTTLE.

Witnesses:

W. S. SAWYER,
A. L. GENTHNER.

Correction in Letters Patent No. 1,160,568.

It is hereby certified that in Letters Patent No. 1,160,568, granted November 16, 1915, upon the application of Edward Kirby Bottle, of Elmira, New York, for an improvement in "Apparatus for Removing Staples," an error appears in the printed specification requiring correction as follows: Page 1, lines 17-18, strike out the words "method and"; and that the said Letters Patent should be read with this correction therein that the same may conform to the record of the case in the Patent Office.

Signed and sealed this 14th day of December, A. D., 1915.

[SEAL.]

R. F. WHITEHEAD,

Acting Commissioner of Patents.

Cl. 254—26.
